UNITED STATES PATENT OFFICE.

MELLEY M. WHEELER, OF WINNSBORO, TEXAS.

POTATO-CUTTER.

No. 880,057.

Specification of Letters Patent.

Patented Feb. 25, 1908.

Application filed May 4, 1907. Serial No. 371,914.

To all whom it may concern:

Be it known that I, MELLEY M. WHEELER, citizen of the United States, residing at Winnsboro, in the county of Wood and State of Texas, have invented certain new and useful Improvements in Potato-Cutters, of which the following is a specification.

The present invention relates to certain new and useful improvements in vegetable cutters, and more particularly to a novel form of seed potato cutter, the primary object being to provide a device of this character by means of which a potato can be quickly and easily divided into a plurality of segments such as are employed for planting purposes.

The invention also aims to design a potato cutter which is simple and inexpensive in its construction and comprises few and durable parts which can be easily manufactured and assembled to produce the finished machine.

For a full description of the invention and the merits thereof and also to acquire a knowledge of the details of construction and the means for effecting the result, reference is to be had to the following description and accompanying drawings, in which:

Figure 1 is a perspective view of the seed potato cutter constructed in accordance with the present invention. Fig. 2 is a vertical sectional view through the same, portions being broken away.

Corresponding and like parts are referred to in the following description and indicated in all the views of the drawings by the same reference characters.

Specifically describing the invention the numeral 1 designates the base, one end of which serves as a support for the knife carrying standard while the opposite end has the hopper 2 arranged thereon. Projecting laterally from the first mentioned end of the base are the arms 3 having the companion standards 4 extending upwardly therefrom.

A cross bar 5 connects the extremities of the standards 4 while a second cross bar 6 joins intermediate portions of the standards, the said cross bars being formed with corresponding openings within which the knife carrying plunger 7 is slidably mounted. Projecting upwardly from the opposite sides of the hopper 2 is a lever support comprising the inclined braces 8 having one end of the operating lever 9 pivotally mounted between the upper ends thereof. This operating le-

ver is pivotally connected to the upper end of the plunger 7 and forms a means for reciprocating the same. The knife 10 which is applied to the lower end of the plunger 7 has a peculiar formation and comprises a plurality of blades 11 radiating from a common center and provided at their outer ends with upwardly and inwardly extending arms 12 connected to the head 13. The portion of the base 1 immediately below the knife 10 is formed with cut away portions or slots 14 corresponding to the blades 11 and designed to receive the same when the plunger is lowered in order to enable the knife to make a clean cut and completely sever the various segments of the potato or other member being operated upon. A coil spring 15 surrounds that portion of the plunger 7 between the two cross bars 5 and 6, the ends of the spring engaging respectively the lower cross bar 6 and a projection 16 upon the plunger. The tension in the spring 15 normally holds the knife and plunger in a raised position so that upon the operation of the device the potato can be placed under the knife and the lever then pressed downwardly in order to bring the knife into engagement with the potato, the said knife being automatically retracted when the pressure upon the lever is released. The hopper 2 which consists of upright walls on opposite sides of the base is designed to contain the potatoes to be cut and guide flanges 17 projecting upwardly from the base form a channel leading from the mouth of the hopper to the portion of the base under the knife. In the operation of the device the potatoes are fed by hand from the hopper to the knife. It will of course be understood that if found desirable the head 13 carrying the blades 11 can be removed from the plunger 7 and a different type of knife substituted therefor and the said knife may be retained in position by any suitable means such as the set screw shown.

Having thus described the invention, what is claimed as new is:

In a device of the character described, the combination of a base, a pair of companion standards projecting from opposite sides of the base at one end thereof, spaced cross bars connecting the standards, a reciprocating plunger guided in its movements by the cross bars, a knife carried by the lower end of the plunger and adapted to coöperate with the base; a coil spring surrounding the plunger

between the spaced cross bars and operating to hold the plunger normally in an elevated position, a lever for actuating the plunger, and a pair of upright walls on opposite sides of the base at the other end thereof, the said walls constituting a hopper and facing towards the knife

In testimony whereof I affix my signature in presence of two witnesses.

MELLEY M. WHEELER. [L. s.]
